JP	1331588 S	4/2008

Primary Examiner — Robin V Webster*Assistant Examiner* — Rachel Voorhies(74) *Attorney, Agent, or Firm* — Cermak Nakajima & McGowan LLP; Tomoko Nakajima(57) **CLAIM**

The ornamental design for link for sprinkler head, as shown and described.

DESCRIPTION

FIG. 1 is a front elevational view of a link for sprinkler head showing my new design;

FIG. 2 is a rear elevational view thereof;

FIG. 3 is a right side elevational view thereof; left side elevational view thereof being a mirror image;

FIG. 4 is a top plan view thereof;

FIG. 5 is a bottom plan view thereof; and

FIG. 6 is a front perspective view thereof.

FIG. 7 is a cross-section view taken along the line 7-7 shown in FIG. 2; and,

FIG. 8 is a cross-section view taken along the line 8-8 shown in FIG. 2.

1 Claim, 8 Drawing Sheets(56)
